UNITED STATES PATENT OFFICE.

JASPER H. BOWLING, OF OZONE, TENNESSEE.

COKE-OVEN.

SPECIFICATION forming part of Letters Patent No. 769,246, dated September 6, 1904.

Application filed May 22, 1902. Serial No. 108,472. (No model.)

To all whom it may concern:

Be it known that I, JASPER H. BOWLING, a citizen of the United States, residing at Ozone, in the county of Cumberland and State of Tennessee, have invented a new and useful Improvement in Coke-Ovens, of which the following is a specification, reference being had to the accompanying drawings.

My invention relates particularly to what are known as "beehive" coke-ovens.

The object of my invention is to provide for a uniform heating of the bed of coal which is being coked and to provide convenient and effective mechanism for utilizing the gases resulting from the coking process and for eliminating and saving by-products from such gases.

My improved construction permits the conducting of the gaseous products during a portion of the stage of coking from one oven into passages beneath an adjacent oven and burning such gaseous products while passing beneath said adjacent oven for the purpose of heating the latter oven.

My improved mechanism also permits the withdrawal of all the gaseous products from the oven in which they are generated and passing them through suitable apparatus for separating by-products and eliminating impurities and then returning the purified gas and burning it under an adjacent oven. Broadly speaking, these steps of operation above recited have been heretofore described by others.

My present invention does not relate to an improved method, but to an improved mechanical construction.

In the accompanying drawings, Figure 1 is a side elevation of an apparatus embodying my improvement. Fig. 2 is a plan of the same apparatus. Fig. 3 is a plan and partial section of a portion of a battery of ovens, enlarged, with reference to Fig. 2. Fig. 4 is a vertical section of an oven through its door. Fig. 5 is a vertical section, the upper portion being on the line 5^a 5^a and the lower portion being on the line 5^b 5^b of Fig. 6. Fig. 6 is a horizontal sectional view illustrating in detail the passages beneath the ovens. Figs. 7,

8, and 9 illustrate details of the tiles used in forming the passages beneath the ovens.

The ovens constituting a battery are preferably arranged in two parallel rows, as shown by the drawings. Each individual oven is substantially like all the others. In some instances it may be desirable to vary the relative location of the parts in the ovens located at the ends of the battery. The general description of one pair of ovens is applicable to all. A retaining-wall 1 extends around the battery of ovens. Said wall rests upon a foundation 2. From the level of the upper portion of said foundation the space inclosed by said foundation is preferably filled with a bed of sand 3, which serves to reduce the loss of heat from the ovens supported upon said bed. The main body or ring wall of the oven 4 is supported upon said bed 3, and within said ring wall is the floor 5, which also rests upon said bed 3. Said ring wall 4 supports the crown 6, and said crown supports the trundle-head 7. Above said trundle-head and communicating with the latter is a chute 8, provided with a removable cover 9. A pipe 10 also communicates with said trundle-head and has joined to its outer end a pipe 11, and the latter communicates with the descending pipe-flue 12, the connection and operation of which will be hereinafter described. A door 13 is located at one side of the oven, and in line with said door an opening 14 extends through the retaining-wall 1. The portion of said retaining-wall above said opening is shown as being supported by arched bars 15.

At one side of the oven there is located beneath the floor 5 a horizontal main inlet-flue 16 at right angles to the retaining-wall, which it penetrates, and parallel to said flue 16 and at the opposite side of the oven is located a similar outlet main flue 18. These flues are connected by a series of parallel flues 17, located at right angles to said flues 16 and 18. Each of said main flues 16 extends through the adjacent portion of the retaining-wall 1 and is provided where it extends through such wall with a suitable door 16^a for the admission of air when the gases passing through said flue are to be burned and to afford access to

said flues for the removal of ashes. The opposite ends of said flues are closed. The main flues 18 also extend through the retaining-wall 1 and are provided with similar doors 5 18^a. At their opposite ends said flues 18 open in the flues 23^a of the chimneys 23. With the exception that the flues 16 are closed at their inner ends and the flues 18 communicate with the chimneys said main flues may be 10 identical in construction. The lower portion of each may be constructed of brick, as shown in Fig. 5. Immediately above said brick portion are the cross-flues, extending from one of the main flues to the other. Said cross-flues are preferably so constructed as to completely occupy all of the space between said main flues, and said cross-flues are preferably of such construction as will permit the largest amount of heat to be delivered from 20 the gases in said cross-flues through the bottom of the oven to the end that the lower portion of the charge to be coked shall be well and uniformly heated.

To adapt said floor to conduct the greatest 25 amount of heat, the walls of said flues and the portion of the floor structure located above said flues should be as thin as is consistent with the strength necessary for supporting and manipulating the charge. I find that 30 such strength and conductivity can be best attained by the floor construction which I have illustrated.

Said cross-flues are constructed of the intermediate tiles 19 and end tiles 20. (Illustrated by Figs. 7 and 8.) Said tiles are preferably 35 rectangular in cross-section and provided with telescoping ends, whereby tight and strong joints are made. Said tiles rest upon the bed of sand 3 and are laid closely against each 40 other in order that the meeting vertical walls of said tiles may support each other, whereby a maximum of strength is attained. The upper wall at one end of each tile 20 is cut away to form horizontal seats 20^a for receiving and 45 supporting one end of the plate-tile 21. Said plate-tiles are large enough to extend from the ends of the tiles 20 across the main flue and rest upon the brickwork at the opposite side of said main flue.

50 Upon the level surface formed by the upper faces of the tiles 19 and 20 between the plate-tiles 21, are placed floor-tiles 22. These are preferably arranged crosswise of the cross-flues in order that each individual floor-tile may 55 be supported as far as possible by the vertical walls of the cross-flue tiles and edgewise upon said tiles and with the joints of said floor-tiles alternating in the adjoining rows, as shown in the upper left-hand oven in Fig. 3. This construction is adapted for the placing of a 60 minimum of material between said cross-flues and the interior of the oven consistent with the strength necessary for withstanding the weight and manipulation of a charge and with-

standing the heating and cooling incident to 65 the operation of the oven.

At one end the inlet main flue 16^a communicates with the flue 12, already described as leading down from the pipes 10 and 11 from the adjacent oven. (See Fig. 5.) The main 70 outlet-flue 18 of the same oven, as already described, leads to the chimney 23. Thus we have a flue leading in single form from the interior of one oven to an adjoining oven and passing in multiple beneath said adjoining oven and thence in single form into a chimney. 75

An inspection of Figs. 4 and 6 will show that my peculiar construction exposes the largest possible floor area to contact with said 80 gases.

A gas-main 24 extends along each side of the battery of ovens, preferably a little above the doors, and a branch pipe 25 leads from the interior of each oven to said main 24, and a cut-off valve 25^a is preferably located in each of said branch pipes to the end that communication between any oven and the main may be cut off when desired. Said gas-main 24 also extends around one end of the 90 battery of ovens (see Fig. 2) and is suitably joined to a main 26, leading to suitable apparatus for eliminating by-products and impurities from gases and to a suitable gas-holder. It is deemed unnecessary to illustrate and describe such eliminating and purifying apparatus and holder, for they do not constitute a part of this invention and are well known to the art. A gas-main 27, similar to the main 24, extends around the battery of ovens near the base of the latter, and branch pipes 28 lead from said main 27 into the main inlet-flues 16. Said branch pipes 28 are provided with suitable cut-off valves 28^a, whereby communication between any 105 main inlet-flue and the gas-main 27 may be cut off. A main 27^a leads from said holder into said main 27.

The operation is as follows: Assuming that all of the ovens of one battery are cold, but 110 charged with coal ready for operation, then the charge in one of the ovens—for example, the oven A, Fig. 2—is ignited and allowed to burn approximately twenty-four hours, (if forty-eight-hour coke is to be made,) the 115 cover or cap 9 of the chute 8 being during such period removed, so that the products of combustion may pass upward through the trundle-head 7 and said chute into the atmosphere, the door 13 being open sufficiently for admission of air to support combustion. Said cap is then placed over said chute, so that the gaseous products can no longer pass upward through said chute, but are compelled to pass laterally through the pipes 10 and 11 and downward through the pipe or down-flue 12 into the main inlet-flue 16 of the oven B and from said main flue in parallel streams through 125

the parallel cross-flues 17 into the main outlet-flue 18 and along the latter into and upward through one of the flues 23^a of the adjacent chimney 23. If so preferred, these 5 gaseous products may be permitted to traverse the course just described without further combustion than results from the admission of air through the door of the oven A; but it is preferable to admit air through the door 10 16^a of the main flue 16 of said oven B and permit said air to mingle with said gaseous products and cause the complete combustion of said products while passing through said main flues and cross-flues to the end that the 15 floor of the oven B may be heated to the greatest extent and the distillation of the charge in said oven B facilitated. The door 13 of the oven B is preferably at this time closed against the admission of air.

20 As soon as distillation begins in the oven B the cover or cap 9 is placed on the chute 8 on the oven B and the chimney-flue 23^a of the oven B covered. Then the valve 25^a in the branch pipe 25 is opened to allow the gaseous 25 products to pass from the interior of the oven B into the gas-main 24 and through the latter to the eliminating and purifying apparatus and the holder, hereinbefore mentioned. Thus the products of distillation in the oven 30 B are saved until the time has arrived for beginning the operation in the adjoining oven C, a period of approximately twenty-four hours. Then the cap or cover 9 is placed upon the chute 8 of the oven C and the cover removed from the chimney-flue of the oven C and the gaseous products made to pass through the flues beneath the oven C, (by the closing 35 of the valve 25^a of the oven B,) whereby the charge in said oven becomes heated.

40 During the first period of operation upon a charge in the oven C the chute 8 on said oven and the corresponding chimney-flue 23^a are closed, and the gases generated in said oven are withdrawn through the gas-main, as 45 already described in connection with the oven B. After said first period the gases from said oven C are passed on beneath the oven D, whereby the operation upon the charge in the oven D is begun. Thus one oven after another 50 is set into operation until the oven adjoining the one which was first set into operation is reached. In Fig. 2 the oven H is the last in the series. When operation upon the first charge in the oven A was completed, said oven 55 was recharged and a new charge operated upon by the heat remaining in the walls of the oven from the previous operation and by heat produced through burning gas from the return gas-main 27. Thus each new charge in the 60 oven A is operated upon by the combustion of gas from said gas-main 27 until finally all the ovens of the entire series have been successively put into operation, and the oven H at the beginning of the second period of op-

eration upon its first charge is ready to deliver gases beneath the oven A.

If so desired, when making forty-eight-hour coke instead of starting the entire series of ovens successively the alternate ovens may be started simultaneously; but in that case all 70 the gaseous products of the first twenty-four hours in the alternate ovens must be allowed to pass into the atmosphere and be lost. By starting the ovens successively or in series the gaseous products of the first twenty-four hours 75 need be sacrificed from only the first oven.

It is to be observed that during the first twenty-four hours of the operation, the period when the interior of the oven is in communication with the gas-mains, the gaseous products of distillation are given off in the largest 80 volumes and greatest variety. Hence my apparatus and the method of operating provide for saving and utilizing the larger and more valuable portions of said products.

If at any time during the first period of operation upon a charge in any oven there is danger of overheating the branch gas-pipe 25, leading from said oven, the valve of said pipe should be closed and the cap 9 of said oven removed, so as to allow the escape of 90 gases from said oven into the atmosphere until such time as they are needed for heating the bottom of the adjoining oven.

The gas stored in the holder may be returned through the mains 27^a and 27 and admitted through the branch pipes 28^a into the main flues 16 of any oven and burned under such oven to any extent that may be desired either in connection with or independently of the gaseous products of distillation coming from the last preceding oven of the same battery. If the last preceding oven should from any cause be out of operation, the gases from the holder may be used as a substitute for the 100 gases which would be coming from the last preceding oven if the latter were in operation.

By means of my improved floor construction and the arrangement of the main flues and cross-flues every portion of the floor of the oven may be uniformly heated and to any degree necessary for causing the coking process at the bottom of the charge to keep pace with the progress of the operation in the upper portion of the charge. Thus the heat 115 imparted to the upper portion of the charge is not lost by conduction and radiation into the lower portion of the charge by reason of the relative coolness of the latter. This makes possible more rapid operation and also 120 makes possible the bringing of all portions of the charge to only such temperature as will transform the coal into coke and avoid the formation of "black-jack" through insufficient heating at the bottom of the oven and forming an excess of ashes and cinders by 125 excessive combustion at the top of the charge.

When the operation upon a charge has been

completed, it is desirable to speedily cool the oven sufficiently for the withdrawal of the charge. By means of my peculiar construction and arrangement of main flues and cross-flues beneath the oven by the opening of the door 16^a a large volume of air can be speedily passed through said flues beneath the oven, whereby the temperature of the floor of the oven and the lower portion of the charge is speedily reduced. This method of reducing the temperature of the charge obviates the necessity of introducing the large amount of water ordinarily introduced into beehive coke-ovens for the cooling of the charge.

15 The portions of the main flues 16 and 18 extending below the level of the cross-flues 17 are adapted to receive ashes precipitated from the gaseous currents passing through said flues. Access for this purpose may be had through the doors 16^a and 18^a. Since said flues are straight, said ashes may be withdrawn by means of a long-handled shovel or scraper. If ashes precipitate into the cross-flues to an objectionable extent, they may be removed into one of the main flues by means of a blast of steam or air delivered from a pipe extended into the other main flue and having a lateral nozzle adapted to be directed into the cross-flues.

25 An even flow of gases through the cross-flues may be attained by partially closing the flues through which there may be an excessive flow of gases. This may be accomplished by means of brick or clay.

30 The door 13 should be some form of mechanical door permitting quick closing in order that the inflow of cool air may be immediately arrested after a charge has been drawn to the end that the internal heat of the oven may be preserved, particularly the heat in the crown of the oven. When the door is promptly closed, the heat of the crown is radiated downward upon the new charge as fast as the latter is introduced. At the same time the charge receives the heat remaining in the bottom of the oven after the closing of the door. The average time from the drawing till the complete insertion of the new charge is approximately one hour. The preservation of the heat of the oven is considered so important that at times when there is a breakdown or a shortage of coal with which to make a new charge the old charge of coke is left smoldering in the oven for the purpose 45 of keeping the interior of the oven heated until the new charge can be received. By using a door which can be quickly closed the charge may be removed the door promptly closed, and the heat of the oven retained for 50 hours.

I claim as my invention—

1. In a battery of beehive coke-ovens, the combination with an oven, of a substantially straight, horizontal main flue located adjacent to one side of and below the floor of said oven

and communicating at one end with the exterior, a similar main flue located at the opposite side of said oven, a chimney with which said second flue communicates, a plurality of substantially straight and parallel cross-flues 7c extending from the first-mentioned flue to the second, and a flue leading from the interior of an adjacent oven into said first-mentioned main flue, substantially as described.

2. In a battery of beehive coke-ovens, the combination with an oven, of a substantially straight, horizontal main flue located adjacent to one side of and below the floor of said oven and communicating at one end with the exterior, a similar main flue located at the opposite side of said oven, a chimney with which said second flue communicates, a plurality of substantially straight and parallel cross-flues extending from the first-mentioned flue to the second, and a flue leading from the interior 80 of an adjacent oven into said first-mentioned main flue, said main flues being of greater depth than said cross-flues, substantially as described.

3. In a battery of beehive coke-ovens, the combination with an oven, of a substantially straight, horizontal main flue located adjacent to one side of and below the floor of said oven and communicating at one end with the exterior, a similar main flue located at the opposite side of said oven, a chimney with which said second flue communicates, a plurality of substantially straight and parallel cross-flues extending from the first-mentioned flue to the second, and a flue leading from the interior 85 of an adjacent oven into said first-mentioned main flue, said cross-flues being constructed of tile of rectangular cross-section and said main flues having their upper walls composed of plate-tiles resting by one edge upon the 90 tiles which form said cross-flues, substantially as described.

4. In a beehive coke-oven, a floor structure comprising prismatic tiles arranged side by side to form parallel cross-flues, brick-shaped 11 tile located upon said prismatic tiles, the tiles at the ends of said cross-flues having seats, 20^a, parallel main flues extending along the ends of said cross-flues and having their upper wall consisting of plate-tiles supported 11 along one edge by said seats, 20^a, substantially as described.

5. A battery of beehive coke-ovens having flues beneath their floors, a flue extending from the coking-chamber of one oven to the floor-flues of an adjacent oven, a similar flue extending from the interior of such oven to the floor-flues of a third oven, and so on with all the ovens, the last of said ovens being thus connected with the first, whereby said ovens are connected in a circuit, a gas-main located adjacent to said ovens, a valved gas-pipe leading from the interior of each oven into said gas-main, a second gas-main located adjacent to said ovens, and a valved gas-pipe 11

leading from said second gas-main into the floor-flues of each oven, substantially as described.

6. In a battery of beehive coke-ovens, the combination with an oven, of a substantially straight, horizontal main flue located adjacent to one side of and below the floor of said oven and communicating at one end with the exterior, a similar main flue located at the opposite side of said oven, a chimney with which said second flue communicates, a plurality of substantially straight and parallel cross-flues extending from the first-mentioned flue to the second, a flue leading from the interior of an adjacent oven into said first-mentioned flue, a gas-main located adjacent to said ovens, a valved gas-pipe leading from the interior of each oven into said main, a second gas-main located adjacent to said ovens, and a valved gas-pipe leading from said second gas-main into the main flue of each oven, substantially as described.

7. In a beehive coke-oven, provided with parallel main flues, a floor structure comprising prismatic tiles arranged side by side to 25 form parallel cross-flues connecting said main flues, and brick-shaped tile located upon said prismatic tiles, substantially as described.

8. In a beehive coke-oven, provided with parallel main flues, a floor structure comprising prismatic tiles arranged side by side to 30 form parallel cross-flues connecting said main flues, brick-shaped tile located upon said prismatic tiles, and main flues with which said cross-flues communicate, substantially as described. 35

In testimony whereof I have signed my name, in presence of two witnesses, this 8th day of May, 1902.

JASPER H. BOWLING.
